STEAM TURBINE AND SPEED CONTROLLING
MECHANISM THEREFOR

Christopher A. Schellens, Marblehead, Mass., assignor to C-S Engineering Company, Englewood, N. J., a corporation of Delaware

Application November 19, 1935, Serial No. 50,577

22 Claims. (Cl. 253—59)

This invention relates to steam turbines and to speed governing devices therefor, and particularly to safety devices for preventing excessive rotative speeds of the turbine.

5 A steam turbine is commonly provided with a device for preventing the turbine wheel from rotating at a dangerously high speed at times when there is not sufficient load on the turbine to keep the speed down to a safe value or when the speed 10 governing device associated with the turbine fails to operate properly to adjust the high pressure steam supply of the turbine to the load on the turbine.

It will be appreciated that the turbine speed, 15 when the turbine is insufficiently loaded and is supplied with unthrottled steam, can be high enough to cause the bursting of the turbine wheel or other damage due to the high centrifugal forces created.

20 The over-speed protective, or speed limiting, device of the turbine, at the present time, consists essentially of speed responsive means associated with the turbine shaft and operable upon excessive rotative speed of the wheel to actuate 25 a valve in the high pressure steam supply to the turbine to shut off the supply of steam. This arrangement necessitates a shaft or some other movable part which projects outwardly through a high pressure steam chamber of the turbine, or 30 the shut off valve associated therewith, which part has to be packed against steam leakage. The over-speed protective device may not be called upon to operate for long periods of time, and hence the operating shaft or part that extends 35 through the high pressure casing is liable to become stuck in the casing due to the depositing of scale on the rod at the packing, corrosion of the rod outside the packing, and the like. This is especially true on turbine driven centrifugal 40 pumps on locomotives used for supplying the boilers thereof with feed water, wherein the locomotive, at times, necessarily has to use hard water, and wherein the pumps are sometimes neglected. Thus the over-speed preventing device may be 45 rendered inoperative.

An object of the present invention is the provision of a device for controlling the speed and particularly for preventing the over-speeding of a steam turbine, wherein the necessity for the 50 location of parts thereof in chambers of different steam pressures and the use of steam packings is avoided.

A further object of the invention is the provision of a device for controlling or limiting the 55 speed of a steam turbine wherein the device is

arranged to control the escape of exhaust steam from the turbine rather than to control the supply of high pressure steam to the turbine, as has been the practice heretofore.

A yet further object of the invention is the provision of a turbine speed controlling or limiting device that is located in the exhaust steam chamber of the turbine casing and acts to control the flow of exhaust steam from the casing so as to eliminate the necessity for extending parts of 10 the device through steam tight packings, whereby to provide a device that can remain indefinitely in operative condition.

Another object is the provision of a turbine speed controlling or over-speed preventing device that is not deleteriously affected by scale 15 deposits.

A further object is generally to improve the construction and operation of speed regulating and over-speed preventing devices for steam turbines. 20

Fig. 1 is a sectional elevation through a steam turbine embodying the present invention.

Fig. 2 is a detail of the speed limiting mechanism of Fig. 1 in an operated position thereof.

Fig. 3 is an end view of the speed responsive 25 weights of Figs. 1 and 2.

Fig. 4 is a section taken along line 4—4 of Fig. 3.

The turbine embodying the present invention is particularly adapted for driving a centrifugal pump for supplying feed water to a locomotive 30 boiler, although the invention is applicable to other turbines.

The turbine includes a bearing bracket 10 having in one end a bearing 12 which rotatably supports the turbine shaft 14. The bracket is provided integrally with a wheel casing 16 that is open at the front end and is closed by a removable cover 18. A turbine wheel 20 is mounted on and secured to the turbine shaft within the casing by means including a nut 22 screwed onto the 35 shaft. The turbine wheel is provided with a row of buckets 24 which receive steam from a series of nozzles 26 in a nozzle plate 28 carried internally by the casing part 16 and receiving high pressure steam from a chamber or inlet passage 30 40 of said casing part. The low pressure exhaust steam is discharged from the buckets of the wheel into the interior of the casing and ultimately is discharged therefrom to the atmosphere or other receiving means. 45

The cover 18 on its inner face is provided with an upstanding post 32 which traverses the axial line of the turbine shaft and which is spaced forwardly of the inner face of the cover 18 and is laterally spaced from said plate so that the ex- 50 55

haust steam has free access to the front and rear faces of the post. The post is hollow or is provided with an exhaust steam passage 34 which communicates with an exhaust steam passage 36 in the casing part 16. Said passage 36 communicates with an outlet opening 38. The front and rear walls 40 and 42, respectively, of the post are apertured to snugly receive a valve casing 44 therein, the valve casing consisting of a circular front plate 46 and a circular rear plate 48 connected together and spaced apart by a series of peripherally spaced bridges 50. The plates 46 and 48 are provided with circular exhaust steam openings or ports 52 and 54, respectively, therethrough. Said openings are disposed concentrically with the axis of the turbine shaft 14 and preferably, although not necessarily, the opening 52 is larger than the opening 54, for a purpose that will presently appear.

20 The turbine shaft is provided with an extension 56 which extends coaxially through the openings 52 and 54 and at its end, beyond the rear wall 42 of the exhaust steam post, has a nut 58 screw-threaded thereon, the nut having a circular periphery. A valve sleeve 60 encircles said shaft extension 56 and said nut and is slideable axially on said nut and is connected thereto against rotation independently thereof by pins 62 that are carried by said nut and extend 25 loosely into axially elongated slots 64 formed in the end of the sleeve 60. The sleeve at the end adjacent the turbine wheel is provided with an inwardly directed radial flange 66 that encircles and is supported for axial motion upon the shaft extension 56, the flange having a hub 68 that bears upon an enlargement 70 of the shaft. A compression spring 72 is located within the sleeve 60 and bears at one end against the flange 66 and at the other end against the nut 58 and thereby 30 tends to urge the sleeve constantly in an axial direction toward the turbine wheel and to maintain the inner end of the sleeve in engagement with internal radial flanges 74 of speed-responsive weights 76.

45 Said weights, as shown clearly in Figs. 3 and 4, have semi-cylindrical bodies 78 which surround the inner end of the sleeve 60 and have outstanding semi-circular flanges 80 at their inner ends which are located within a recess of a collar 82 50 screw-threaded upon the hub 84 of the turbine wheel. The spring 72 under conditions of normal speed of the turbine wheel serves to maintain the flanges 74 and 80 against the flat radial face of the collar 82. The collar is provided with 55 an annular shoulder or ledge 86 which closely surrounds the flanges 80 of the weights to retain them in cooperative relation with said collar 82. When the turbine speed becomes excessive the weights due to centrifugal force tend to become 60 displaced into some position as indicated by the dotted lines and thereby pivot on the edges of the flanges 80 against the collar 82 at the inner edge of the annular ledge 86 thereof, thereby displacing the sleeve 60 toward the left and effecting 65 the throttling of the exhaust steam outlet.

The sleeve 60 is provided with two annular outstanding axially spaced valve discs or flanges 88 and 90, respectively, each of which cooperates 70 respectively with a separate one of valve ports or openings 52 and 54 in the valve casing 44 of the exhaust steam post. The discs 88 and 90 are but slightly smaller in diameter than the ports 52 and 54 so that they can enter and substantially close said ports although there is sufficient clearance 75 between the valve discs and the walls of the

ports to permit the discs to rotate with the turbine without any rubbing contact between the discs and the valve casing.

When the turbine is rotating at normal speed the parts are in the position illustrated in the full lines of Fig. 1. When, however, the turbine rotates at an excessive speed the weights 78 become displaced outwardly into some position as illustrated in Fig. 2, and hence force the sleeve 60 axially towards the right against the action of 10 the spring 72 and thereby position the valve discs 88 and 90 within the valve ports 52 and 54. In this position the exhaust steam passage of the turbine is substantially closed and hence the flow of steam through the turbine buckets is reduced 15 at least to such an extent that the no-load speed of the turbine is held down to a safe value.

It will be appreciated that the discs 88 and 90 do not make an absolutely steam tight fit within the ports 52 and 54 as the small clearance is desirable to prevent wear on the valve casing due to the rotation of the turbine. Thus a small amount of steam can pass from the turbine casing into the exhaust passage even when the valve discs are within the ports. It will also be appreciated that steam can escape from the turbine casing through the shaft packing gland 92 and also through the condensate drain 94 passing through the bottom wall of the casing part 16 and opening into the exhaust passage 36. Nevertheless, the mechanism above described throttles the exhaust steam outflow to such an extent that the amount of steam that can pass through the turbine buckets is so little that the turbine speed is held down to a safe value. The turbine casing is, of course, made strong enough to withstand the high pressure steam that exists therein at such time. The windage losses are greatly increased by the high pressure and cooperate in holding the turbine speed down to a safe 40 value.

It is desirable to provide an attendant with a warning signal that the over-speed device has operated. This warning signal is conveniently in the form of a steam whistle 96 which is connected 45 through a spring loaded valve 98 with the wheel chamber. The valve is maintained closed under normal low pressures of exhaust steam in the chamber but opens automatically upon the occurrence of high steam pressure caused by the operation of the over-speed preventing device and thereby allows steam to pass into the whistle to sound the warning signal. The steam capacity of the whistle is made small enough not to deleteriously influence the speed of the turbine wheel. 50

If the valve discs 88 and 90, instead of being of different diameters, are made of the same diameter the over-speed device is then balanced against movement in any direction by the exhaust steam pressure within the casing so that the device is then responsive only to movements of the centrifugal weights. It is preferred, however, to have the disc 88 larger than the disc 90 for the following reason. When the discs are within the valve ports and the exhaust steam passage is then substantially closed, there is a relatively high steam pressure within the wheel casing and hence there is a corresponding high axial thrust on the turbine shaft since the turbine wheel is an outboard wheel and one end of the shaft is terminated within the wheel casing. However, by having the disc 88 sufficiently larger in diameter than the disc 90 there is provided an axial thrust on the shaft through the larger valve disc operating in the opposite direction to the 75

5 direct thrust on the shaft, when the discs are within their corresponding valve ports and the sleeve 60 is bearing against the pins 62, as illustrated in Fig. 2. This oppositely directed thrust 5 can be made to offset the thrust on the shaft so that there is no substantial axially directed shaft displacing force.

10 The increased diameter of the disc 88 over the disc 90 is also desirable in providing a rapid or snap closing of the exhaust ports. It will be appreciated that while the sleeve 60 is substantially balanced so far as its movement in response to exhaust steam pressure is concerned when the discs are remote from the exhaust steam ports, 15 when, however, the discs are close enough to the ports to exert a throttling effect on the steam passing therethrough, there will be a considerably greater pressure toward the right on the disc 88 than toward the left on the disc 90 and hence the sleeve will be moved rapidly into a 20 port closing position. Furthermore with the sleeve in this position it will tend to be held there by the steam pressure until the steam supply to the turbine is shut off by an attendant, and the 25 tendency to periodic opening and closing of the ports by the sleeve, or hunting, will be minimized. Obviously, however, if these advantages 30 are not desired the discs 88 and 90 can be made the same diameter so as to provide a structure that is balanced against movement due to the steam pressures thereon.

35 The spring 72 is preferably so adjusted as to be unstable in an outwardly displaced position of the centrifugal weights so that when these weights have become substantially displaced the spring is unable to maintain the weights in the displaced position but will yield and permit the weights to be further displaced into their maximum and exhaust valve closing position.

40 It will be appreciated that by throttling the exhaust steam rather than by throttling the high pressure inlet steam, as has been the case heretofore, a speed limiting device is obtained wherein all the operative parts are in the same body of steam so that steam tight packings and other closely fitting parts can be eliminated and thus 45 the device can remain inoperative for long periods of time and yet operate surely when required.

50 It will also be noted that since all moving parts of the device are carried by the turbine shaft and hence are subjected to centrifugal force, that water of condensation is thrown therefrom so that there is little likelihood of scale being deposited on the parts to hinder the free operation thereof. Where considered necessary passages, such as the passages 100 formed in the cylindrical wall 78 of the centrifugal weights, have been 55 provided to permit the ready escape of water of condensation and the structure has otherwise been designed to render it immune from impairment of operation due to scale deposit.

60 While the invention has herein been explained in its adaption for use primarily as an over-speed preventing device it can also be used as a speed regulating device to maintain a constant speed of the steam turbine wheel. For such use the valve discs 88 and 90 preferably will be of the same diameter and the spring 72 will be so 65 adjusted that it tends to maintain the centrifugal weights stably in any displaced position thereof, corresponding with certain speeds, thereby to hold the discs 88 and 90 in throttling positions with respect to the exhaust ports as determined 70 by the displaced positions of the weights. The

use of the device as a speed governor may be valuable for certain purposes but in general is not recommended where the pressure of the incoming steam is sufficiently high to necessitate the use of an expansion nozzle in directing the steam 5 into the turbine buckets, since the speed controlling effect obtained by throttling the exhaust steam outlet is relatively small under such condition, until relatively high exhaust steam pressures are obtained, as compared with throttling 10 the high pressure inlet steam. Where extreme uniformity of speed is not necessary, however, or where the pressure of the inlet steam does not demand an expansion nozzle, the device is useful for maintaining an approximately uniform 15 turbine speed.

I claim:

1. In a turbine, a turbine wheel, means providing an inlet passage for steam to the wheel, means providing an outlet passage for exhaust 20 steam from the wheel, said outlet passage having an entrance port that is co-axial with the wheel, and speed responsive means carried by and rotatable with said wheel and including a valve member on said shaft movable in response 25 to the speed of the wheel into throttling relation with said port.

2. In a steam turbine, a turbine casing, a turbine wheel therein, a shaft on which said wheel is mounted, said casing having an inlet passage 30 for guiding steam to said turbine wheel, said casing also having a passage for exhaust steam therefrom, means providing said exhaust passage with an entrance port that is co-axial with said shaft, and port controlling means comprising a 35 member movable axially on said shaft toward and away from throttling relation with said port, and means responsive to the speed of said wheel for moving said member into throttling relation with said port.

3. In a steam turbine, a turbine casing, a turbine wheel therein, a shaft on which said wheel is mounted, said casing having an entrance passage guiding steam to said wheel, said casing also having means providing an outlet passage for the exhaust steam therein and a pair of opposed 45 exhaust steam entrance ports open to the exhaust steam space of said casing and axially aligned with said wheel shaft, a valve member carried by and movable axially on said shaft having a pair of valve members each controlling a separate port, and means responsive to the speed of said wheel for moving said valve members into throttling relation with said ports.

4. In a steam turbine, a turbine casing, a turbine wheel therein, a shaft on which said wheel is mounted, said casing having an inlet passage guiding steam to said wheel, said casing also having a hollow exhaust post confronting the axis of said wheel and provided with co-axial ports 60 that are co-axial with said wheel and open to the interior of said post, said casing having an outlet passage for exhaust steam communicating with the interior of said post, a valve member carried by and movable axially on said shaft 65 and having valve elements each confronting a separate port, and means responsive to the speed of said shaft for moving said valve member axially to position said elements into throttling relation with said ports.

5. In a steam turbine, a turbine casing comprising an open-ended body part and a cover for the open end thereof, a turbine wheel within the wheel chamber of said casing, a shaft on which said wheel is mounted, said casing hav- 75

ing an entrance passage guiding steam to said wheel, said casing also having an exhaust steam passage conducting steam from the interior of said casing, said exhaust steam passage being located both in said body part and in said cover, 5 said cover having a port co-axial with said shaft and opening into said exhaust passage, and wheel-speed responsive means carried by said shaft controlling the flow of exhaust steam 10 through said port.

6. In a steam turbine, a turbine casing comprising an open-ended body part and a cover for the open end thereof, a turbine wheel within the wheel chamber of said casing, a shaft on which 15 said wheel is mounted, said casing having an entrance passage guiding steam to said wheel, said casing also having an exhaust steam passage conducting steam from the interior of said casing, said exhaust steam passage being located 20 both in said body part and in said cover, said cover having a port co-axial with said shaft and opening into said exhaust passage, wheel-speed responsive means carried by said shaft controlling the flow of exhaust steam through said 25 port, said exhaust steam passage of said body part being located in part below said wheel chamber, and said casing having a bleed passage extended from the bottom of said wheel chamber into said part of said exhaust steam passage.

7. In a steam turbine, a turbine casing comprising an open-ended body, a cover therefor, a turbine wheel in said casing, a shaft on which 30 said wheel is mounted, said casing having an inlet passage conducting steam to said wheel and also having an exhaust passage conducting 35 exhaust steam from the interior of said casing, said cover having an upstanding hollow post therein the interior of which post forms a part of said exhaust passage, said post being disposed in the axis of said shaft and having opposed entrance ports in its opposite walls, a sleeve movable axially on said shaft having a pair of valve 40 elements each of which is disposed in throttling relation with a separate port, and wheel-speed responsive means carried by said shaft and wheel 45 and operable to move said sleeve axially into throttling relation with said exhaust steam ports in response to excessive wheel speeds.

8. In a steam turbine, a turbine wheel, a shaft on which said wheel is mounted, means providing 50 an entrance for guiding steam into said wheel, means providing an outlet passage for exhaust steam from said wheel including an entrance port for said exhaust steam passage disposed co-axially with said shaft, a port-throttling valve 55 member mounted on said shaft and movable axially thereof into and away from throttling relation with said port, said valve member being arranged to fit closely within said port in the 60 throttling position thereof but to be free from contact with the wall of said port so that it can rotate without rubbing against the wall of said port, and means responsive to the speed of said wheel for controlling the axial movements of said 65 valve member.

9. In a turbine, a turbine casing, a turbine wheel therein, a shaft on which said wheel is mounted, said casing having an inlet passage guiding steam to said wheel, said casing also having a hollow part surrounding said shaft and provided with a pair of opposed circular ports co-axial with each other and with said shaft and opening to the interior of said casing and to said 70 hollow part, a valve sleeve mounted on said shaft 75 for conjoint rotation therewith but free for axial

movement thereon extended through said ports and having annular outstanding flanges constituting valve discs each disposed to throttle a separate port, a compression spring encircling said shaft within said sleeve and arranged to urge 5 said sleeve for axial movement along said shaft away from said ports, and centrifugal means responsive to the speed of said wheel for moving said sleeve axially in a port throttling direction.

10. In a steam turbine, a turbine wheel, a shaft 10 on which said wheel is mounted, means providing an inlet passage guiding steam to said wheel, means providing an exit passage for exhaust steam from said wheel, said exit passage having an entrance port, and means responsive to the 15 speed of said wheel for throttling said exhaust steam entrance port and including means responsive to the difference in exhaust steam pressures in and in front of said entrance port for actuating said speed responsive means rapidly 20 into full port throttling position.

11. In a steam turbine, a turbine wheel, a shaft on which said wheel is mounted, means providing an inlet passage guiding steam to said wheel, means providing an exit passage for exhaust steam from said wheel, said exit passage having an entrance port, and means responsive to the 25 speed of said wheel for throttling said exhaust steam entrance port and including means for actuating said speed responsive means rapidly 30 into full port throttling position, said last named means being responsive to exhaust steam pressure.

12. In a steam turbine, a turbine casing, a turbine wheel therein, a shaft on which said wheel 35 is mounted, said casing having an inlet passage guiding steam to said wheel, said casing also having an exhaust steam duct provided with opposed entrance ports for the exhaust steam to flow out of said casing, one of said ports being 40 larger than the other, a valve member having large and small discs respectively confronting said large and small ports, means guiding said valve member for movement toward and away from said ports, and means responsive to the 45 speed of said wheel for moving said valve member in a port throttling direction, said large valve member being responsive to exhaust steam pressure within said casing and operable thereby to move rapidly into port throttling position independently of the action of said speed responsive 50 means.

13. In a steam turbine, a turbine casing, a turbine wheel therein, a shaft on which said wheel is mounted, said casing having an inlet 55 passage guiding steam to said wheel, said casing also having an exhaust steam duct provided with opposed entrance ports for the exhaust steam to flow out of said casing, one of said ports being larger than the other, a valve member having 60 large and small discs respectively confronting said large and small ports, means guiding said valve member for movement toward and away from said ports, means responsive to the speed of said wheel for moving said valve member in a 65 port throttling direction, said large valve member being responsive to exhaust steam pressure within said casing and operable thereby to move rapidly into port throttling position independently of the action of said speed responsive means, and 70 spring means acting on said sleeve to move it away from port controlling position upon a sufficient reduction of wheel speed and steam pressure within said casing.

14. In a steam turbine, a turbine wheel, a shaft 75

on which said wheel is mounted, means providing an inlet passage guiding steam to said wheel, means providing an outlet passage for exhaust steam, and means actuated by a predetermined increase of wheel speed with said outlet passage and additionally influenced by the exhaust steam pressure for rapidly throttling said outlet passage.

15. In a steam turbine, a shaft, a turbine wheel mounted on said shaft, a casing providing a wheel chamber in which said wheel is rotatable and an exhaust steam duct under said chamber, said duct having an entrance to said chamber above the bottom thereof, means for governing the flow of exhaust steam through said duct, and means providing a bleed passage from the bottom of said wheel chamber into said duct.

16. In a turbine, a shaft, a turbine wheel on said shaft, a wheel casing having an exhaust steam outlet concentric with said shaft, a valve on and rotatable with said shaft and movable axially thereof into throttling relation with said outlet and being free from rotating engagement with the outlet wall, means normally holding said valve away from said outlet, and centrifugal means responsive to the speed of said wheel for moving said valve toward said outlet.

17. In a turbine, a shaft, a turbine wheel on said shaft, a wheel casing having an exhaust steam outlet concentric with said shaft, a valve on and rotatable with said shaft and movable axially thereof into throttling relation with said outlet and being free from rotating engagement with the outlet wall, means normally holding said valve away from said outlet, and centrifugal means responsive to the speed of said wheel for moving said valve toward said outlet, said centrifugal means being carried by said shaft and rotatable with it and said valve.

18. In a turbine, a shaft, a turbine wheel on said shaft, a wheel casing having an exhaust steam outlet concentric with said shaft, outlet-throttling valve means on and rotatable with said shaft and movable axially thereof toward and away from said outlet, and centrifugally-controlled means carried by said shaft to operate said valve means.

19. In a steam turbine, a shaft bearing, a shaft in said bearing having an end overhanging said bearing, an over-hung turbine wheel on said overhanging shaft end, a casing providing a wheel chamber in which said wheel is rotatable, means providing an exhaust steam duct having an entrance to said wheel chamber on the side of said wheel opposite said bearing and aligned coaxially with said shaft, valve means controlling said entrance mounted on and rotatable with said shaft and movable axially thereof toward and away from said entrance, and shaft speed responsive means mounted on and rotatable with said shaft having an operative connection with said valve means.

20. In a steam turbine, a shaft, a turbine wheel mounted on said shaft, a casing providing a wheel chamber in which said wheel is rotatable and an exhaust steam duct a part of which is below the wheel, said duct having an entrance to said chamber above the bottom thereof, means for governing the passage of exhaust steam into said entrance, and means providing a bleed passage from said chamber into said duct, said bleed passage having an entrance into said wheel chamber below said wheel and an outlet into said exhaust steam duct part below said wheel.

21. In a turbine, a rotatable wheel structure, a housing about said structure having an exhaust steam outlet, a speed responsive valve supported by said structure and located adjacent the axis thereof for movement into throttling relation with said outlet, and speed-responsive mechanism separate from said valve supported by and rotatable with said wheel structure and valve having connection with said valve operative to move it into throttling relation with said outlet.

22. In combination in a turbine, a turbine wheel and shaft structure, a wheel casing having an exhaust steam outlet co-axial therewith, outlet throttling valve means on and rotatable with said structure and movable axially thereof toward and away from said outlet, and centrifugally controlled means carried by said structure to operate said valve means.
